UNITED STATES PATENT OFFICE.

GEORGE H. CAMP, OF LEOLYN, PENNSYLVANIA.

RAIL FASTENER.

Application filed November 25, 1921. Serial No. 517,659.

To all whom it may concern:

Be it known that I, GEORGE H. CAMP, citizen of the United States, residing at Leolyn, in the county of Lycoming and State 5 of Pennsylvania, have invented certain new and useful Improvements in Rail Fasteners, of which the following is a specification.

The present invention relates to rail fasteners and particularly to means for holding 10 the rail firm.

An object of the invention is to provide an improved type of rail fastener having means adjustable into engagement with the rail for holding the same firm, the said holding means being, in turn, provided with 15 means for connecting it to a tie.

A further and additional object of the invention is to provide an improved tie plate formed of separable and adjustable sections 20 having rail-engaging clamps and provided with improved means for locking the sections to the supporting tie.

Various other objects and advantages of the invention will become apparent during 25 the continuance of the following description.

In the drawings:—

Figure 1 is a plan view of one end of a supporting tie showing the manner of applying the invention thereto.

Figure 2 is a vertical longitudinal section taken on line 2—2 of Figure 1.

Figure 3 is a vertical cross section taken on line 3—3 of Figure 1, and,

Figure 4 is a perspective of the removable or adjustable section of the rail fastener.

Referring more in detail to the drawings, 10 indicates an end portion of a supporting tie, and 11, the rail section to be supported thereon. The invention is in the form of a tie-plate comprising separable sections 12 and 13.

Section 12 consists of a substantially heavy plate having its bottom surface provided with a transversely extending rim 14 sharply pointed to bite into the tie for anchoring the plate thereto against any shifting movement during the passage of heavy rolling stock over the rail. At a point beyond the rib in the direction of the inner 50 end of the plate, the width of the latter is reduced to provide a cut out along the bottom surface as indicated at 15. This cut out is adapted to receive the base flange 16 of the adjustable section 13 which is slidable longitudinally of section 12 and between 55 guides 17 and 18. Guides 17 and 18 are in-

tegral with section 12, being provided by bifurcating the inner portion of the latter, thus forming a slot as indicated by the dotted line structure 19 of Figure 1.

Integral with the upper face of section 12 is a rail-clamping portion 20 spaced inwardly from the terminal of slot 19 to provide a rail seat 21 for the flange of the rail. Clamp 20 overlaps the rail base on one side 65 to provide a suitable socket for the rail flange which is held firmly in place by a similar rail-clamping portion 22 integral with the inner end of top plate 23 of the adjustable section 13. Plate 23 is held in 70 vertically spaced relation from bottom plate 16 by means of an intermediate body portion 24, which is adapted to be received in the space or slot between guides 17 and 18. Both the top plate and the base flange of the 75 adjustable section overlap the edges of the intermediate portion 24 and provide steadyng flanges on opposite sides of the guides to insure steady movement of the adjustable section besides serving to lock the same 80 against vertical displacement. Each section is provided with a pair of vertically disposed openings extending from the upper to the lower surface as indicated at 25 and 26. Opening 25 is adapted to receive a suitable fastener, such as a spike 27, the shank of which extends down into the tie to secure the section thereto. The other opening, which is in proximity to a side edge of its respective section receives the shank 28 of a spike-locking member having a radially projected head 29. The head is of a length sufficient to enable it to be swung over the top or head of the spike and is provided on its under surface with a cavity or socket for the 90 spike-head as indicated at 30.

Upon the upper surface of the head, a suitable gripping handle 31 is provided to permit the convenient swinging of the locking head. The shank of the locking device is provided with a spiral groove in which is engaged one end of a pin or stud carried by each section for operation in the spiral groove to cause the lifting or lowering of the shank as the head is swung in the arc of a circle. This arrangement is indicated generally by numeral 32 and, as is obvious, permits the locking device to automatically engage or disengage itself from the head of the spike when turned.

In assembling the invention, the stationary section 12 is first placed upon one end

of the tie and spiked into place so as to form a firm steady support for rail 11 which is then placed on the rail seat 21 of the section. The adjustable section 13 is then slid inwardly of the slotted end of section 12 until the rail is firmly clamped to the seat, after which spike 27 may be driven to hold the adjustable section in its adjusted position, the spike lock being then adjusted to 10 prevent any loosening of the head. It will thus be seen that the invention requires but the use of a single fastener for each section and when together forms a rail-chair in which the rail is securely held. It may also 15 be pointed out that the rail is seated on a solid portion of the plate and to one side of the joint between the sections thereby offering a strong and durable structure capable of successfully withstanding the shocks and 20 strains exerted by the passage of heavy rolling stock.

From the foregoing it is believed that the advantages and novel features of the invention will be readily understood and there-

fore further detailed description is deemed unnecessary.

What is claimed is:—

A rail fastener comprising a tie plate of separable sections, one of said sections being stationary and having its bottom surface provided with a rib pointed to bite into the tie for anchoring the plate and being reduced beyond the rib to provide a cutout along the bottom surface, the other section being slideable between guides on the stationary section and having a base flange engaged in the cut out of the latter, a rail clamp integral with the upper face of the stationary section, a rail clamp integral with the inner end of the adjustable section, a fastener extending thru an opening in each section, and a lock member passing thru adjacent openings in the said sections and having a head movable into engagement with the said fastener to hold the same secure. 45

In testimony whereof I affix my signature.

GEORGE H. CAMP.
